UNITED STATES PATENT OFFICE.

LOUIS WOJIDKOW, OF BROOKLYN, NEW YORK.

DESIGN FOR A COVER.

SPECIFICATION forming part of Design No. 27,934, dated December 7, 1897.

Application filed October 20, 1897. Serial No. 655,859. Term of patent 31 years.

To all whom it may concern:

Be it known that I, LOUIS WOJIDKOW, a citizen of the United States, residing at Brooklyn, county of Kings, and State of New York, have invented and produced a new and original Design for a Cover for Hollow Ware, of which the following is a specification, reference being had to the accompanying drawings, forming part thereof.

10 Figure 1 is a plan view of a cover for hollow ware, showing my new design; and Fig. 2 is a broken side view of the same.

As shown in the drawings, the leading or material feature of my design consists of a 15 series of radial ridges between which are formed panel-like depressions.

The cover A is provided with a convex body formed with an abrupt-rising apex B, which is crowned by a knob-shaped projection C,

while the rim D of the cover is flattened and curved, as shown. Extending from a point on the abrupt apex B near the knob-shaped projection C to a point near the rim D are a series of sharp-cornered or angular radial ribs or ridges e, between which are formed deeply- 25 depressed panel portions E.

Having described my invention, what I claim is—

A design for a cover for hollow ware, substantially as herein shown and described. 30

In testimony that I claim the foregoing as my invention I have signed my name in presence of two subscribing witnesses.

LOUIS WOJIDKOW.
